UNITED STATES PATENT OFFICE

2,672,967

COIN OR TOKEN OPERATED DEVICE

Ernest E. York, Falmouth Corner, Maine, assignor to American Coin Changer Corp., Boston, Mass., a corporation of Maine

Application December 1, 1950, Serial No. 198,599

3 Claims. (Cl. 194—1)

1

By invention relates to an improvement in coin or token operated devices and more particularly relates to an improvement in automatic machines such as are used in the vending of beverages, confections and other products.

In the case of such machines it is necessary to prevent or arrest the acceptance of coins during delivery of the product and during periods when the machine is out of product. Where the machine is of the type delivering change with the product, when change is due, it is further necessary to prevent the acceptance of coins of a value greater than the price of the product when the number of coins in the change magazine is inadequate to make the required change. The present invention is especially concerned with machines of the latter type.

The means employed to accomplish the above functions conventionally comprises a plurality of coin "reject" arms mounted adjacent the coin tracks through which the coins are caused to travel subsequent to their classification. Each of these arms is hingedly mounted on its support and is spring- or weight-loaded so that the arm is constantly urged toward the corresponding coin track, which is suitably apertured to receive a finger carried by the arm, the finger being adapted to deflect coins traveling the track into a chute extending to a coin return box. In its normal position the arm is held away from the coin track by an electromagnet which forms part of the electrical system of the machine and is de-energized only during delivery of the product or on the machine arriving at one of the other conditions previously indicated.

My invention has for its principal object to provide reject arms which may be employed in a machine of the change-making type, whether the machine is set for operation by the lowest denomination of coin accepted by the machine or by a coin of a value intermediate the value of the lowest denomination of coin accepted and the value of the highest denomination of coin accepted. Always heretofore it has been necessary in the changing of the setting of such machines to install a completely new set of reject arms, a procedure which is quite time-consuming and frequently beyond the capabilities of the route man or other individual charged with attending the machine.

I shall particularly describe my invention with reference to the accompanying drawings illustrating the same as applied to a machine accepting coins of three values. For the purpose of

2

the description, it will be assumed that the accepted coins are nickels, dimes and quarters. In the drawings,

Fig. 1 is a sectional view of a portion of a vending machine, taken along line 1—1 of Fig. 1a;

Fig. 1a is a diagrammatic plan view showing the arrangement of the coin chutes;

Fig. 2 is a view in elevation, partly diagrammatic, taken at right angles to Fig. 1, and

Figs. 3—6 are isometric detail views of reject members conforming to the invention.

Referring first to Fig. 1, the numeral 10 denotes a conventional slug rejector-coin classifier unit receiving coins through the usual slot in the casing of the machine. The classified coins are directed into coin tracks or passageways 14, 16 and 18, track 14 being the dime track, track 16 the nickel track, and track 18 the quarter track. Coins received by track 12 are coins detected as spurious by the unit 10.

Adjacent track 18 is a coin return chute 20 extending to a coin return box or dish, not shown, which may be formed in the casing of the vending machine. Chute 20 communicates with the tracks 12, 14, 16 and 18 via branch chutes 21, 21, 22 and 24 respectively, coins entering chute 21 from the track 14 passing through an opening 26 in the left-hand side wall of such track, then rearwardly into chute 21.

Fixed to a supporting plate 28 (Fig. 2) behind the rear walls of the coin tracks 14, 16 and 18, which walls will be noted as apertured at 11, 15 and 17, are a pair of bracket members 30 and 32, each of which has an electromagnet 34, 36 secured to its vertically disposed portion. These brackets serve as supports for reject members 38 and 40 respectively, the reject members being hingedly connected to the arms 42, 44 of the brackets at the ends thereof. A tension spring 46 anchored to reject member 38 and the corresponding bracket tends to swing the reject member toward the coin tracks, while a spring 48 exerts a similar effect on reject member 40. Normally, this action is prevented by the electromagnets which, when energized, attract the reject members.

In accordance with the invention, reject member 38 (Figs. 5 and 6) is formed to comprise a fixed finger 50 and a pivoted arm 52 carrying a finger 54 integral with the arm. A spring 56 anchored to the body of the reject member and to the arm 52 operates to hold the arm in either of two positions, as indicated by the stops 58 and 60.

Reject member 40, like member 38, comprises (Figs. 3 and 4) a finger 62 integral with the body

thereof and a pivoted arm 64 carrying a finger 66. Arm 64 is held in either of two positions, as indicated by the stops 68 and 70, by a tension spring 72 anchored to the body of the reject member and to the finger 66 at a point near its base.

The setting of the pivotally mounted arms 52 and 64 is determined by the setting of the machine, reference being made in this connection to Fig. 1 wherein the straight dot lines indicate the position of the arms when the machine is set for vending a five-cent article, while the dot-and-dash lines indicate their position when the purchase price of the article is ten cents. It is believed evident that on a change in the setting of the machine, the necessary adjustment of the reject members consists simply of lowering one of the pivoted arms and raising the other. This markedly speeds the change-over as a whole, which is obviously advantageous, particularly when it is considered that in the usual case the machine is just one of perhaps several hundred, all of which must be adjusted.

A typical vending machine, equipped according to my invention, operates as follows:

MACHINE SET TO DISPENSE A FIVE-CENT ARTICLE

Operation with a five-cent piece (Product in the machine)

The nickel enters the five-cent track from the slug rejector-coin classifier unit. Finger 62 of reject member 40 being held out of the track by the electromagnet 36, the coin passes the level of the aperture 15 to strike a coin actuatable switch arm therebelow. Closing of the switch energizes the vending circuit, resulting in delivery of the product. The circuit including the electromagnets is open during the delivery period irrespective of the coin used to operate the machine; accordingly any coin inserted during such period is diverted into the coin return chute 20.

The five-cent piece actuating the switch arm is directed into a vertically disposed tubular change magazine positioned over a pair of solenoid controlled slides apertured in correspondence with the diameter of a five-cent piece, the apertures registering with each other and with the chamber of the magazine. The lower slide has the thickness of a five-cent piece, the upper the thickness of three five-cent pieces. Any excess five-cent pieces directed to the tubular magazine are deflected to a coin collection box.

Operation with a five-cent piece (No product condition)

The nickel enters the five-cent track as before but is diverted by finger 62 into chute 20 for return to the patron, this action following from the fact that the electromagnets are in circuit with a switch which is opened on the machine running out of product.

Operation with a ten-cent piece (Product in the machine and change in the change magazine)

The coin enters the ten-cent track, i. e., track 14, passing the level of the aperture 11 into engagement with a switch arm therebelow. Closing of the switch completes the vending circuit and also completes a circuit including the solenoid controlling the ten-cent slide under the change magazine. Accordingly, the patron receives a single five-cent piece in addition to the merchandise.

Operation with a ten-cent piece (Machine out of product or supply of five-cent pieces in change magazine exhausted)

Finger 54 being in the coin track 14, the coin is deflected through the opening 26 into the chute 21, connecting with the coin return chute 20.

Reject member 40 or, more accurately, electromagnet 36 is not in circuit with the switch controlled by the level of nickels in the change magazine, hence the machine continues to accept nickels during periods when it will not accept dimes or quarters because of an inadequate supply of nickels in the magazine.

Operation with a twenty-five-cent piece (Product in the machine and change in the change magazine)

The coin is directed into the quarter track, i. e., track 18, and passes the level of the aperture 17 into engagement with a switch arm therebelow. Closing of the switch energizes the vending circuit and also the circuit including the solenoids, both of which are actuated to deliver four five-cent pieces with the merchandise. During delivery of the merchandise, the electromagnets are de-energized as usual so that any coins inserted are returned to the patron via the chute 20.

Operation with a twenty-five-cent piece (Machine out of product or change)

The coin is diverted into the chute 20 for return to the customer. If the machine is out of change only, nickels continue to be accepted.

MACHINE SET TO DISPENSE A TEN-CENT ARTICLE

As previously explained, this setting as to the reject members involves nothing more than raising arm 52 of reject member 39 and lowering arm 40 of reject member 40.

Nickel operation

Assuming the machine is not out of product, the first nickel, on passing the level of the aperture 15, strikes an arm which is thereby positioned to actuate the ten-cent switch when struck by the second nickel. On this happening, the vending circuit is energized and the product delivered. The nickels are directed to the tubular change coin magazine now mounting only one apertured slide of a thickness corresponding to that of three five-cent pieces.

During delivery of the product, both electromagnets are de-energized, any coin inserted during the delivery function consequently being directed into the chute 20 for return to the patron. This applies irrespective of the coin used to operate the machine.

Ten-cent operation

Assuming product in the machine, the coin passes the level of the aperture 11 into engagement with the ten-cent switch arm. Closing of the switch energizes the vending circuit.

Since electromagnet 36 is not in circuit with the switch controlled by the level of coins in the change magazine, the machine continues to accept nickels and dimes when it will not accept quarters due to an inadequate number of coins in the magazine. On the machine running out of product, however, the electromagnet is de-energized.

Quarter operation

The quarter enters the track 18 and, assuming product and change in the machine, passes the

level of the aperture 17 into engagement with a switch arm therebelow. Closing of the switch energizes the vending circuit and the change circuit, the patron receiving three five-cent pieces with his purchase.

Having thus described and illustrated my invention what I claim is:

1. In a coin operated vending machine having a plurality of coin tracks for reception of coins of different values, a coin reject member mounted for movement toward and away from said tracks, said reject member having a first deflector fixed thereto for entry into one of said tracks upon movement of said member toward said tracks, and a second deflector pivotally mounted thereon swingable to and from a position to enter another of said tracks and a position in which it will not enter any of said tracks upon movement of said reject member toward said tracks.

2. In a coin operated vending machine having a plurality of coin tracks for reception of coins of different values, a spring-biased coin reject member mounted for swinging movement toward and away from said tracks, and means for moving said member against said spring loading, said reject member having a first deflector fixed thereto for entry into one of said tracks upon movement of said member toward said tracks, and a second deflector pivotally mounted thereon for snap action to and from a position to enter another of said tracks and a position in which it will not enter any of said tracks upon movement of said reject member toward said tracks.

3. In a coin operated vending machine, the combination of a plurality of coin tracks for the reception of coins of low, intermediate and high value, each said track having an aperture therein, a pair of reject members mounted for movement to and from said coin tracks, each said member being biased for movement toward said tracks, and means for restraining each said member against such movement, the first said reject member having a deflector fixed thereto in position to enter the aperture in the high value coin track and a second deflector pivotally mounted thereon swingable to and from a position to enter the aperture in said intermediate value coin track and a position in which it will not enter said aperture upon movement of said first reject member toward said tracks, said second reject member having a deflector fixed thereto in a position to enter the aperture in the low value coin track and a second deflector pivotally mounted thereon swingable to and from a position to enter said aperture in said intermediate value coin track and a position in which it will not enter said aperture upon movement of said second reject member toward said tracks.
